REMOVABLE WINDOW CASE STRUCTURE

John P. Francis, 20 Boston St., Haverhill, Mass. 01830
Continuation-in-part of design application Ser. No.
19,899, Nov. 3, 1969. This application Oct. 2,
1970, Ser. No. 25,311

Term of patent 14 years

The portion of the term of the patent subsequent to
Mar. 9, 1985, has been disclaimed

Int. Cl. D25—02

U.S. Cl. D13—1

FIG.2

FIG.3

FIG.5

FIG.6

FIG. 1 is a perspective view of a removable window case structure, embodying my new design,

FIG. 2 is a side elevation view thereof,

FIG. 3 is a top plan view thereof,

FIG. 4 is a perspective view of another form of the invention wherein a top cover is employed,

FIG. 5 is a side elevation view thereof, and

FIG. 6 is a top plan view thereof.

The window structure fragmentarily shown in broken lines in FIGS. 1 to 6 inclusive is included for illustrative purposes only.

This is a continuation-in-part of design application Ser.

No. D. 19,899, filed Nov. 3, 1969, now Pat. No. D. 220,091.

I claim:

The ornamental design for a removable window case structure, substantially as shown and described.
